UNITED STATES PATENT OFFICE.

ARTHUR CASELTON, OF LEICESTER, ENGLAND, ASSIGNOR TO UNITED SHOE MANUFACTORY COMPANY, OF PATERSON, NEW JERSEY, A CORPORATION OF NEW JERSEY.

LASTING-MACHINE.

1,108,969.

Specification of Letters Patent.

Patented Sept. 1, 1914.

Application filed October 2, 1911. Serial No. 652,270.

To all whom it may concern:

Be it known that I, ARTHUR CASELTON, a subject of the King of England, residing at Leicester, in the county of Leicester, England, have invented certain Improvements in Lasting-Machines, of which the following description, in connection with the accompanying drawings, is a specification, like reference characters on the drawing indicating like parts in the several figures.

This invention relates to lasting machines, and more particularly to a tread engaging member or work rest for use in such machines for supporting the work, or acting as an abutment against which the work is pressed during the lasting operation.

The invention will be described in connection with a lasting machine of the type in which a single pincer operates upon successive portions of the upper, as disclosed, for example, in United States Letters Patent No. 584,744, but it is to be understood that it is not limited to use with such type of machine.

When the work rest is used in connection with a machine of the type referred to it will be constructed to project into such a position that the insole of the shoe being lasted can be pressed against the rest while the projecting edge of the upper will be in position to be engaged by the pincers or grippers.

An object of the invention is to improve the tread rest, in such a manner that it will automatically adapt itself to the surface of the insole and hold it more securely for the operation of the machine notwithstanding that the disposition of the said surface changes somewhat in its horizontal relationship to the machine.

A work rest constructed according to this invention also permits a ready tipping of the shoe to raise or lower the work surface at either side of the machine while still maintaining the bottom of the last in firm contact with the rest.

The invention can with particular advantage be applied to a lasting machine such for example as that shown in United States Letters Patent No. 1,007,051, granted October 31, 1911, which includes mechanism for inserting two tacks at each cycle of the pincers' operation upon certain parts of the work, as by its application to such machine it is insured that both tacks are driven to an

equal extent. Accordingly, a feature of the invention is the provision for a lasting machine of a tread rest or work support that is automatically adjusted by its contact with the work to suit variations in the inclination of the adjacent marginal portion of the shoe bottom.

Conveniently, the tread rest or work support having the characteristics above set forth may also be arranged to automatically adjust itself in other directions by swiveling at right angles to the swiveling motion first mentioned, or otherwise, so as to compensate for angular disposition longitudinally as well as for lateral displacement out of the horizontal. Another feature of the invention is therefore, a shoe rest or work support for the purpose described that is mounted to swivel both laterally and in a direction at right angles to the said lateral swiveling movement.

Another feature of the invention comprises for a machine for lasting boots and shoes in which there is capacity for inserting a plurality of fasteners, the combination with a tread face engaging member that is automatically adjusted by its contact with the work to suit variations in the inclination of the adjacent marginal portion of the shoe bottom, of connections actuated by the said adjustment so to control the fastener-inserting mechanism that each fastener will be inserted to a predetermined level relatively to the adjacent tread surface notwithstanding variations in the level of that surface.

The invention will now be described as to one form or embodiment, but it is to be understood that although the constructions described are of a preferred character the invention is not to be regarded as confined to the exact arrangement set forth, but that it may be varied as to the number, form and disposition of the parts and their method of operation, as well as applied to machines other than that of the particular type shown.

In the drawings: Figure 1 is a side elevation, partly sectional, of sufficient of a lasting machine to enable the tread rest or work support of this invention to be understood, and shows said rest in the position which it occupies when in use; Fig. 2 is an enlarged view in transverse section of the tread rest, on the line 2—2, Fig. 1; Fig. 3 is a plan view, and Fig. 4 a side elevation of the

tread rest on a somewhat enlarged scale; Fig. 5 is a view similar to Fig. 1 but showing an operative connection between the tread rest or work support and the fastening-inserting mechanism to control the 5 stroke of the drivers; Fig. 6 is a front elevation of the parts shown in Fig. 5; and Fig. 7 is a horizontal section on the dotted line 7—7, Fig. 5.

10 The column 2 of the machine supports the head 4 which is provided with bearings for the usual main shaft carrying cams for effecting the several movements of the lasting instrumentalities. These cams impart 15 to the pincers 5 the closing movement to cause them to seize the edge of the upper, the updrawn movement to lift the upper and stretch it about the last, and the overdraw movement to lay the stretched upper 20 upon the insole. The machine may also be equipped with the usual mechanism for imparting the plating movements to the pincers, and with fastening-inserting mechanism comprising a driver, or drivers, tack-supplying means, such as a raceway, a tack-carrier and tack separator for each driver, and actuating mechanism for these several 25 parts. These instrumentalities together with the cams and their connections for imparting the several movements to the pincers are not illustrated herein, as they form no part of the present invention, but all may be substantially as shown and described in the Letters Patent No. 584,744, above referred to.

30 The tread rest or work support, as illustrated in Figs. 1 to 4, is carried by a bracket 8 supported adjustably, as for example by screws 10 passing through slots in the bracket 8 and entering a projecting portion 40 of the machine head 4. The lower part of the bracket, or as shown in Fig. 1, an arm 14 adjustably secured thereto, has an extended portion 16 that is inclined toward 45 the front of the machine.

50 The portion 16 comprises a bushing or sleeve 18 which receives a stem 20 to the lower end of which is connected a plate 22 that forms the part of the tread rest which 55 engages the insole. The plate 22 may be roughened or grooved as indicated at 24, (Fig. 2), in order to hold the insole securely, and is further provided with a perforated ear or lug 26 adapted to be received between 60 ears 27 forming part of the stem 20, and pivoted thereto by a pin 28. The stem 20 is provided with a flange or collar 30 which rests against one end of the sleeve 18, the stem being prevented from movement along 65 the sleeve in the opposite direction by a collar 32 secured to the stem by a pin 34. The said pin may be made of such a length that a portion will project beyond the collar 32 at one or both ends so as to form a stop 70 to limit the turning movement of the stem

in the sleeve in one or both directions by the engagement of the projecting part or parts of the pin with the arm 14. There may be secured to the projecting portion 16 of the arm 14, as by a screw 17, a leaf spring 35 with its free end bearing on the ears 27 and thereby tending to hold the plate 22 in a substantially horizontal position.

75 From the foregoing it will be seen that the connection of the work-engaging plate 22 with the stem 20 through the pin 28 passing through the lug 26 and ears 27 forms a pivot about which the plate 22 can swivel in one plane, while the connection of the stem 20 with the sleeve 18 forms a second 80 pivot about which said plate can also be swiveled in a direction at right angles to the direction of the first swiveling movement. Obviously a modification of the foregoing is one wherein instead of the work-engaging plate 22 turning about two independent pivots a universal connection, such as a ball and socket joint, could be provided between the work-engaging plate and its 85 supporting bracket.

90 In Figs. 5, 6 and 7 a two tack lasting machine of the type shown in Patent No. 1,007,051 above referred to, is illustrated in which a tread rest or work support, similar to that described in connection with Figs. 95 1 to 4, is included the said rest being connected with fastening-inserting mechanism in such a manner that the stroke of the independent nail drivers will be changed in accordance with changes in the level of the 100 marginal portion of the shoe bottom at the points where the two tacks are driven, as for example when the margin of the shoe is elevated at one side and the rest swiveled out of the horizontal. As illustrated in the 105 drawings these connections comprise a shaft 36 which is carried in a sleeve 38 extending upward from the bracket 8. The shaft 36 carries at its lower end a crown gear wheel 40 which meshes with another crown 110 gear wheel 42 secured on the stem 20 carrying the work-engaging plate 22. At the upper end of the shaft 36 is a bell crank 44, the free end of each arm of which is loosely connected by a link 46 with an arm 48 of an abutment 50 against which a collar 53 on each driver bar 51 abuts in its nail-driving stroke. Each abutment is made in two parts the lower 50¹ of which is stationary 115 and is provided with a cam or wedge surface 54 against which bears a corresponding cam or wedge surface 55 on the upper and rotatable part 50² of the abutment.

120 It will be seen that the inclined surfaces are disposed oppositely to one another so that as the bell crank 44 is turned with the shaft 36 in one or the other direction the upper part 50² of one of the abutments will be raised by the action of the inter-acting 125 cam surfaces while the upper part 50² of 130

the other abutment will be correspondingly lowered. To retain the movable parts of the abutments in their adjusted positions a wedge 58 is located between the adjacent edges of the abutment members 50² in such a manner as to be capable of sliding movements. The forward portion of this wedge carries a stem which slides in an opening in a casing 56, and a spring 59 surrounds the stem and is compressed between the casing and a collar on the stem. This spring acts with a normal tendency to force the wedge into gripping engagement with the rotary abutment members so as to lock them against rotation. The wedge is held out of action while the drivers 51 are raised by a lever 60 pivoted at 62 to an extension of the head 4, the said lever being acted upon by a cam surface 64 carried by one of the driver bars 51. When, therefore, as illustrated in Fig. 5, the driver bars occupy an elevated position an anti-friction roll carried by the upper arm of the lever 60 is engaged by the cam surface 64 which causes an outward movement of the lower arm of said lever and moves the wedge 58 outwardly, compressing the spring 59 and disengaging the wedge from the rotatable abutment members 50², 50², which are thereby rendered free to be adjusted by the movements of the work rest.

By the provision of the operative connection as above set forth between the rest and the fastening-inserting mechanism the height of the abutments 50² which limit the extent of the down stroke of the independent drivers will be altered according to the extent of the displacement of either side of the work-engaging plate 22 and the two tacks can each be inserted to a predetermined level relatively to the adjacent tread surface notwithstanding variations in the level of that surface.

In the use of a lasting machine provided with the devices as above described, and illustrated in Figs. 5, 6 and 7, the pincers are given their usual movements in order to intermittently seize the marginal portions of the upper, stretch it about the last, and lay it upon the insole, and the tack driver bars are raised by the usual lifter against the stress of their springs, and released in suitable time relation to the described pincer movements to cause the drivers to insert two tacks, in spaced relation, for every pulling operation of the pincer, as set forth in Patent No. 1,007,051 above referred to. During these operations the workman holds the shoe in the position shown in Fig. 5 with the insole pressed against the plate 22 of the work rest, which acts as an abutment to resist upward movement of the shoe against the force of the updraw of the pincer, the transversely arranged pivot 28 permitting the plate to rock so as to conform to varying

longitudinal inclinations of the margin of the shoe bottom, and the swiveled stem 20 permitting the plate to rock so as to conform to varying transverse inclinations of the margin of the shoe bottom. During these latter adjustments of the plate through the described connections the driver bar abutments are caused to control the distance traveled by the drivers in accordance with the varying levels of that portion of the shoe in which the fastenings are to be inserted so that said fastenings will always be driven equal distances into the stock.

Having thus described my invention, what I claim as new and desire to secure by Letters Patent of the United States is:

1. In a machine of the class described, a tread rest constructed to be automatically adjusted about predetermined intersecting axes extending substantially perpendicular to one another by contact with the work to suit variations in the inclination of the surface engaged by said rest.

2. In a machine of the class described, a tread rest having a movable work-engaging portion adjustable about predetermined intersecting axes extending substantially perpendicular to one another for variations in the position of the surface engaged thereby.

3. In a machine of the class described, a tread rest provided with a work-engaging portion having provisions for adjustment for variations in the inclination of the work in a transverse direction and also about a predetermined axis extending lengthwise of the shoe.

4. In a machine of the class described, a tread rest provided with a work-engaging portion having provisions for adjustment for variations in the work in a longitudinal direction about a predetermined axis extending obliquely upwardly and outwardly substantially in the median line of the machine.

5. In a machine of the class described, a tread rest provided with a work-engaging portion having provisions for adjustment about predetermined axes extending substantially horizontally and located adjacent to the tread face of the work for variations in the longitudinal and transverse inclinations of the work.

6. In a machine of the class described, a tread rest, and supporting means therefor constructed to permit swiveling movement of the rest in directions transverse to each other, said supporting means having provision for maintaining the rest with its tread engaging face in a predetermined angular position.

7. In a machine of the class described, a support, a stem swiveled to said support, and a tread-engaging member connected to said stem and adjustable to meet variations in the transverse inclination of the work.

8. In a machine of the class described, a

support, a stem swiveled to said support to permit movement about an axis extending lengthwise of the shoe, and a tread-engaging member connected to said stem by a pivot arranged transverse to the axis of the stem.

9. In a machine of the class described, a support, a bearing carried thereby and extending upwardly and outwardly from the machine substantially in the median line of the machine, a stem swiveled in said bearing and having spaced ears at its lower end adjacent to the machine and having at its opposite end stops to limit its swiveling movement, a tread-engaging plate provided with a lug arranged between said ears, and a transverse pivot connecting said lug and ears.

10. In a machine of the class described, a support, a bearing carried thereby and extending upwardly and outwardly from the machine substantially in the median line of the machine, a stem swiveled in said bearing and having spaced ears at its lower end adjacent to the machine and having at its opposite end stops to limit its swiveling movement, a tread-engaging plate provided with a lug arranged between said ears, a transverse pivot connecting said lug and ears, and yielding means acting on said ears for holding the plate in a normal horizontal position in restricting movement of the plate about said transverse pivot and also of the stem in its bearing.

11. In a machine of the class described, a support, a bearing carried thereby, a stem swiveled in said bearing, a tread-engaging member connected with said stem, and means for confining the stem against longitudinal movement in its bearing.

12. In a machine of the class described, a bracket, a bearing carried thereby, a stem swiveled in said bearing, a tread-engaging member connected with said stem, collars for confining the stem to its bearing, and a pin for securing one of said collars to the stem and arranged for engagement with said bracket to limit the swiveling movement of the stem in its bearing.

13. A machine of the class described having, in combination, a pincer and actuating means therefor, and a tread rest for supporting a shoe against the pull of the pincer having capacity for angular adjustment to suit variations in the inclination of the shoe bottom.

14. A machine of the class described having, in combination, a pincer and actuating means therefor, and a tread rest for supporting a shoe against the pull of the pincer constructed for automatic adjustment to suit variations in the inclination of the shoe bottom.

15. A machine of the class described having, in combination, a pincer and actuating

means therefor, and a tread rest for supporting a shoe against the pull of the pincer having provision for angular adjustment to suit variations in the transverse inclination of the shoe bottom.

16. A machine of the class described having, in combination, a pincer and actuating means therefor, and a tread rest for supporting a shoe against the pull of the pincer having provision for angular adjustment to suit variations in the longitudinal inclination of the shoe bottom.

17. A machine of the class described having, in combination, a pincer and actuating means therefor, and a tread rest for supporting a shoe against the pull of the pincer having provision for adjustment to suit variations in the longitudinal and transverse inclinations of the shoe bottom.

18. A lasting machine having, in combination, a pincer, means for inserting a plurality of fastenings at each pincer cycle, and means automatically adjustable by contact with the work to control the driving of the fastenings.

19. A machine of the class described having, in combination, shoe-lasting means, means for inserting a plurality of fastenings at each cycle, and means controlled by variations in the surface of the work to determine the extent to which the fastenings are inserted.

20. A machine of the class described having, in combination, means for working an upper over a last by repeated operations, means for inserting a plurality of fastenings at each lasting cycle, and means to insure the insertion of the fastenings to a predetermined extent irrespective of variations in the level of the shoe bottom.

21. A machine of the class described having, in combination, means for working an upper over a last by repeated operations, means for inserting a plurality of fastenings at each cycle, and automatic means controlled by variations in the level of the shoe bottom to insure the insertion of the fastenings to a predetermined degree.

22. A machine of the class described having, in combination, means for working an upper over a last by repeated operations, means for inserting a plurality of fastenings at each cycle, and means including a tread rest to engage the work constructed to so control the fastening-inserting mechanism that the fastenings will be inserted to a predetermined degree irrespective of variations in the level of the shoe bottom.

23. A machine of the class described having, in combination, a pincer and actuating mechanism therefor, drivers for inserting a plurality of fastenings at each pincer cycle, and a tread rest which is adjustable by variations in the level of the shoe bottom and arranged to so control the action of the

rivers as to insure the driving of fastenings to a uniform level irrespective of such variations.

24. A machine of the class described having, in combination, lasting mechanism, two drivers and actuating means to drive two fastenings at each lasting cycle, and a tread rest and connections arranged to control the stroke of the drivers by variations 10 in the level of the shoe bottom so as to insure the driving of tacks to a uniform depth.

25. A machine of the class described having, in combination, two drivers and actuating mechanism to drive two fastenings, adjustable abutments to determine the stroke 15 of said drivers, and a tread rest adjustable by variations in the level of the work to control the position of said abutments.

26. A machine of the class described having, in combination, two drivers and actuating mechanism to drive two fastenings, stops carried by the drivers, rotarily adjustable abutments to be engaged by said 20 stops, and a tread rest adjustable by variations 25 in the level of the work to control the position of said abutments.

27. A machine of the class described having, in combination, two drivers and actuating mechanism to drive two fastenings, stops carried by the drivers, rotarily adjustable abutments for said stops to vary the 30 stroke of the drivers, means for adjusting said abutments in accordance with variations in the level of the work, and means for locking said abutments in adjusted position 35 arranged to be rendered inoperative when the drivers are raised.

28. A machine of the class described having, in combination, two drivers and actuating mechanism to drive two fastenings, stops carried by the drivers, rotarily adjustable abutments for said stops to vary the stroke of the drivers, means for adjusting 40 said abutments in accordance with variations in the level of the work, a wedge for engaging said abutments to lock them in 45 adjusted position, and a cam carried by one of said drivers and arranged to move the wedge out of engagement with the abutments 50 when said driver is raised.

29. A machine of the class described having, in combination, two drivers and actuating mechanism to drive two fastenings, stops carried by the drivers, adjustable abutments for said stops, a tread rest mounted 55 for swiveling movement to adjust it for variations in the level of the work, and connections between said abutments and tread rest to adjust the stroke of the drivers in accordance with such variations. 60

30. A machine of the class described having, in combination, two drivers and actuating mechanism to drive two fasteners, stops carried by the drivers, adjustable abutments for said stops, a tread rest comprising a 65 plate having a stem mounted for swiveling movement to meet variations in the level of the work, and geared connections between said abutments and stem so constructed and arranged that said abutments will be adjusted to so control the stroke of the drivers that the fastenings will be driven uniform distances irrespective of such variations. 70

31. A machine of the class described comprising lasting means, means for inserting 75 two tacks at each lasting operation, and a tread rest for supporting a shoe against the pull of the lasting means, said tread rest having capacity for automatic adjustment to adapt it to variations in the inclination of 80 that portion of the work in which the fastenings are inserted, and means controlled thereby to cause the fastenings to be inserted a uniform distance irrespective of such variations. 85

32. A lasting machine having, in combination, lasting devices, means including two drivers for inserting two fastenings for each lasting cycle, a tread rest, and means permitting relative adjusting movement of the 90 rest and the two drivers to effect like depths of insertion of the two fastenings on the portions of the shoe bottom which are uneven.

In testimony whereof I have signed my name to this specification in the presence of 95 two subscribing witnesses.

ARTHUR CASELTON.
